CLAIM

The ornamental design for a mounting apparatus, as shown and described.

DESCRIPTION

FIG. 1 is a perspective view of the mounting apparatus showing our new design;

FIG. 2 is a front elevational view of the mounting apparatus shown in FIG. 1;

FIG. 3 is a back elevational view of the mounting apparatus showing in FIG. 1;

FIG. 4 is a side elevational view of the mounting apparatus shown in FIG. 1;

FIG. 5 is a top plan view of the mounting apparatus show in FIG. 1; and,

FIG. 6 is a bottom plan view of the mounting apparatus shown in FIG. 1.
